UNITED STATES PATENT OFFICE.

LUTHER G. TURNER, OF TORRINGTON, CONN., ASSIGNOR TO THE TURNER & SEYMOUR MANUFACTURING COMPANY, OF SAME PLACE.

DESIGN FOR A SHADE-PULL.

SPECIFICATION forming part of Design No. 15,156, dated July 22, 1884.

Application filed February 9, 1884. Term of patent 7 years.

To all whom it may concern:

Be it known that I, LUTHER G. TURNER, of Torrington, in the county of Litchfield and State of Connecticut, have originated and produced a Design for a Shade-Pull, of which the following is a specification.

The design consists in a pendent ball or drop, a surmounting ornamental crown on the exterior of the ball or drop, and a pendent frame surrounding the ball or drop.

The accompanying drawing represents a portion of a shade and a shade-pull embodying my design.

A designates the shade, and B designates the ball or drop pendent from the shade-stick by an eye, a. At the exterior of the upper part of the ball or drop B is a surmounting ornamental crown, b, which adds greatly to

the elegant and attractive appearance of the design. The drop B is pendent within a surrounding frame, C, also pendent from the eye a.

My design above described enables me to produce a shade-pull of very unique and attractive appearance.

What I claim as new, and desire to secure by Letters Patent, is—

The design for a shade-pull, consisting of the pendent ball or drop B, the surmounting ornamental crown b on the exterior of the ball or drop, and the surrounding pendent frame C, substantially as shown and described.

L. G. TURNER.
